UNITED STATES PATENT OFFICE

CAROLUS L. EKSERGIAN, OF DETROIT, MICHIGAN, AND JOHN P. TARBOX, OF PHILADELPHIA, PENNSYLVANIA, ASSIGNORS TO BUDD WHEEL COMPANY, OF PHILADELPHIA, PENNSYLVANIA, A CORPORATION OF PENNSYLVANIA

METHOD OF MAKING WHEEL HUBS

Application filed May 27, 1929. Serial No. 366,268.

In the obtuse angled rolling of hubs together with integral flanges, brake drums, discs or the like, the hub barrels are difficult to form without unduly high temperatures and undue die wear, not to mention the high pressures which affect not only the dies but the bearings and other wearing parts of the machine. This is for the reason that the elongated barrels of the hubs are formed by axially deep dies which are difficult to fill except under high temperature and pressure, and for the further reason that the coring out of the hub is still more difficult to achieve except under temperatures and pressures equally high or even higher. If the barrel is not formed exteriorly and interiorly during obtuse angled rolling operation, there is considerable machining to do. If it were not for this high temperature the condition might be alleviated to some extent by oversize initial formation. But yet further, the attainment of full and adequate cross sections of certain kinds of flanges requires a full feeding of metal radially outward to insure this fullness of section and this full feeding of metal outwardly militates against perfect formation of hub barrel under certain conditions. Yet the process of obtuse angled rolling is at once so economical of metal and cost of production that it is a great asset in the achievement of cheap yet high quality hubs.

The primary object of our invention is to construct hubs by a process which utilizes obtuse angled rolling in such a manner as to obviate many of the foregoing difficulties and to overcome others. The process involves utilization of obtuse angled rolling to form one radial section of the main body of the hub barrel together with an integral flange or brake drum or disc, and another process of forming the remaining radially divided section of the main body of the hub barrel and a subsequent rigid joining of the two together. Specifically, we form integrally by obtuse angled rolling a radially divided section of the main body of the hub barrel and a radial flange intermediate its ends. We cut from preformed tubing of a lesser diameter than the obtuse angled rolled section a section of tubing of a length equal to the length of

the remaining radially divided section of the hub barrel, expand the inboard end thereof substantially to the diameter of the obtuse angled formed section and thereafter butt weld the expanded end of the tubular section to the projected end of the obtuse angled rolled section. 55

In the accompanying drawings we show the process.

Figures 1 to 4 show one modification of our invention, 60

Figure 1 showing an axial cross section of the obtuse angle formed section of the hub barrel and its integral flange,

Figure 2 showing an axial section of a 65 severed length of tubing,

Figure 3 showing a similar section of the same length of tubing with its inboard end enlarged and

Figure 4 showing the formed parts of 70 Figs. 1 and 3 butt welded together.

Figures 5 to 7 show a modification of our invention in a manner similar to the showing in Figs. 1 to 4, and

Figure 8 is a diagram of the obtuse angled rolling operation. 75

The main body of the hub barrel is divided in a radial plane 10 as indicated in Fig. 4. The inboard section of the main body of the hub barrel so radially divided is designated 11 and the integrally formed radial flange intermediate its ends is designated 12. In the illustration this flange also constitutes the head of the brake drum per se 13. The outboard radially divided section of the main body of the hub barrel is designated 14. 80

The inboard radially divided section 11 and its integral flange 12 we form by obtuse angled rolling as indicated diagrammatically in Fig. 8. The axial length of the section 11 is relatively short as compared with that of the section 14 and relatively short as compared with the over-all length of the barrel. Its thickness is considerable as commonly met with in forged hubs. Its flange is likewise of considerable thickness of root and body to give adequate stiffness for the provision of bolt holes, the anchoring of studs and the like securing devices for the 85 100

attachment of wheel bodies thereto demountable or otherwise. Of such dimensions and proportions the structure becomes most readily rollable by obtuse angled process at economical temperatures and pressures, and with perfect and integral flow and distribution of metal for fullness of section and perfect form, even in the matter of the coring out of the center. In fact, in such form the center may 5 be cored out almost to final dimension leaving but a minimum of machining. The flange 12 in such form may or may not carry the brake drum. The brake drum may be separately attached thereto. The flange 12 may 10 be the root of a wheel disc, a spoked wheel body or the like or utilized as a foundation for any other wheel body.

The section 14 we cut from preformed tubing of a diameter less than the rolled diameter 20 of the section 11 and of a length substantially equal to the remaining length of the completed barrel, as indicated in Fig. 2. We then expand the end of this preformed section of tubing by a forging operation to 25 the form shown in Fig. 3 in which the expanded end is substantially equal in diameter to the diameter of the inboard obtuse angled rolled section 11 of the hub barrel. The tube may be preformed in other ways 30 than in long lengths. It may be formed in individual lengths. Suffice it that it is preformed. The expanding operation of the inboard end may be achieved in any desired manner, forging, rolling, spinning and the like but preferably by an axial forging operation achieved by axially disposed dies. The two radially divided sections of the main body and the hub barrel are then welded together, the outwardly projecting end of 35 40 the inboard section 11 to the inwardly projecting expanded end of the outboard section 14.

In the modification of Figs. 5 to 7 the hub is axially divided on a cylindrical surface 15. But obtuse angle rolled section 11 as before 45 is relatively short, and it is also of relatively greater diameter than the internal diameter of the completed hub. The tube formed section 14 is relatively long and of the full length 50 of the barrel. Its external diameter is substantially equal to the internal diameter of the obtuse angle rolled section 11. The two are joined together by arc welding in the cornice as indicated at 16. Of course, the 55 surfaces are appropriately machined after the rolling and tube forming operations and before assembly so that they snugly fit upon each other. Fig. 5 shows the preformed obtuse angle rolled part, Fig. 6 shows the pre-formed tubular part 14 and Fig. 7 the completed product.

It must be realized that all of the showings are relatively diagrammatic, that precise contours, precise dimensions, precise 60 tolerances, etc. are not shown. It must be

evident also that there are yet other modifications of the method of our invention which fall within its generic spirit. These various modifications and variations in form are likewise to be protected to us in the annexed claims. 70

What we claim as new and useful and desire to protect by Letters Patent is:—

1. The method of forming hubs which consists in obtuse angled rolling of the hub flange 75 and one part of the main body of the barrel, and butt welding another part of the barrel to the projecting end of the one part.

2. The method of making hubs which consists in obtuse angled rolling of a radially divided part of a main body of the barrel together with a flange intermediate the ends of that part, and butt welding the other radially divided part to a projecting end of the one part. 80

3. The method of forming hubs which consists in obtuse angled rolling of a radial flange and one radially divided part of the main body of the barrel, forming the other radially divided part of the main body of the barrel from a section of preformed tubing, and butt welding said radially divided parts together. 90

4. The method of making hubs which consists in obtuse angled rolling of the inboard 95 radially divided section of the main body of the hub barrel, in cutting from preformed tubing the outboard radially divided section of the main body of the hub barrel, and butt welding said tube sections of the barrel together. 100

5. The method of forming hubs which consists in obtuse angled rolling of the inboard radially divided section of the main body of the barrel and an integral flange of 105 determinate diameter, forming the outboard radially divided section of the main body of the barrel initially from preformed tubing of a lesser diameter, flaring the inboard end of said section of tubing to the determinate diameter of the obtuse angled rolled section, and thereafter butt welding said sections together. 110

In testimony whereof we hereunto affix our signatures.

CAROLUS L. EKSERGIAN.
JOHN P. TARBOX.
